UNITED STATES PATENT OFFICE.

HENRY KLECKLER AND GLENN H. CURTISS, OF GARDEN CITY, NEW YORK, ASSIGNEES,
BY MESNE ASSIGNMENTS, TO CURTISS ASSETS CORPORATION, OF GARDEN CITY,
NEW YORK, A CORPORATION OF NEW YORK.

TAIL SKID FOR AEROPLANES.

Original application filed March 31, 1916, Serial No. 88,087. Divided and this application filed March 13, 1918. Serial No. 222,215.

To all whom it may concern:

Be it known that we, HENRY KLECKLER and GLENN H. CURTISS, citizens of the United States of America, residing at Garden City, in the county of Nassau and State of New York, have invented certain new and useful Improvements in Tail Skids for Aeroplanes, of which the following is a specification.

10 The present invention, which relates to improvements in aeroplane tail skids, is a division of application Serial No. 88,087 filed March 31, 1916.

It is characterized by the construction of 15 the skid in the form of a block rather than a bar as heretofore. One end of the skid block together with its associated shock absorbing mechanism is enclosed in a suitable casing of streamline form and the latter so 20 arranged relatively to the vertical rudder of the craft as to occupy at all times a pocket or recess formed in the rudder at its base. The type and character of the shock absorbing mechanism is also different from 25 the conventional in that a spring rather than elastic cords, is used. Moreover, the relative arrangement of the tail skid parts render it stronger and better able to withstand and absorb the tail shocks incurred in 30 landing.

Of the drawings:

Fig. 1 is a side elevation of the skid and that portion of the craft in the immediate vicinity thereof.

35 Fig. 2 is a section on the line 2—2 of Fig. 1.

Fig. 3 is an enlarged side elevation of the skid.

Fig. 4 is a top plan view of the skid.

40 Fig. 5 is a longitudinal sectional view of the cushioning devices, and

Fig. 6 is a vertical sectional view of the combined tail and rudder post illustrating, in section, the manner in which the skid is attached.

In the embodiment of the invention selected for illustration the tail skid is designated as an entirety by the numeral 10. It 50 comprises a broad flat skid block 11 which tapers downwardly and rearwardly, and in cross section is of a substantially streamline form. Heel plates 12 are secured as indicated at 13 and 14 to the skid block 11, the

plates together affording means whereby the cushioning device 15 is secured at one end 55 to the block. This device 15, as illustrated in Fig. 3, comprises a rod 16 transversely slotted as indicated at 17, a spring 18, an abutment 19, and an abutment 20, the abutments being located, in the normal position 60 of the skid, adjacent the respective terminals of the rod. A bolt 21 is arranged to pass transversely through the slot 17 in the rod 16, through the abutment 19, and through both heel plates 12, the mentioned 65 bolt affording the connection between the heel plates and the cushioning device or means 15. The abutment 20 is fixed with respect to the rod 16 and located at the opposite end thereof from that within which the 70 slot 17 is formed. The abutment 19 however is movable longitudinally on the rod throughout the length of the slot and against tension of the spring 18. The spring, as stated, 75 embraces the rod 16 and bears at its respective terminals against the opposed abutments.

The opposite end of the rod 16 from that fastened to the heel plates 12 is pivoted as at 22 between extensions 23 of a clip 24 secured rigidly to a sleeve 25 mounted to rotate on a vertical axis about the lower end of a combined tail and rudder post 26. Annular flanges 27 engage the opposite terminals of the sleeve 25 and preclude its longitudinal displacement. A second clip 28 is secured to the sleeve 25 adjacent its lower end, this clip affording a means whereby the skid 11 is pivoted as at 29 between extensions 30 of said clip for movements in a 85 vertical plane. Since the clips 24 and 28 are rigid with the sleeve 25 and the latter is mounted for rotation about the post 26, it is 90 evident that the skid 11 may be freely turned.

In use, the skid upon coming in contact with the ground will yield vertically against the action of the spring 18. As the spring gives the skid swings vertically from the pivot point 29 and the rod swings vertically 100 from the pivot point 22; the abutment 19, during swinging movement of the skid and rod, moving longitudinally of the latter directly against the tension of the spring. The bolt 21, by reason of its fitting engagement 105 in the slot 17 will cause the rod 16 to swing

in a vertical plane or according to the swinging movement of the skid.

Both the skid and its cushioning means are located in a recess or pocket 31 formed in the vertical rudder 32 of the craft. The pocket is formed preferably in the part of the rudder at or near the rudder post so that the axis of the skid (considered in its entirety) is in direct continuation of the axis of the rudder. To minimize resistance during flight a streamline housing or enclosure 33 is arranged to embrace the cushioning means for the skid as indicated in Fig. 1, the said housing 33 completely filling the space 31 when the skid and rudder are vertically aligned.

It is evident from the construction and arrangement of the parts described that movement of the skid in a lateral plane is entirely independent of the lateral swinging movement of the rudder; that the cushioning means or shock absorbing mechanism is located wholly aft of the rudder post and so enclosed by the housing 33 as to offer a minimum of resistance; and that the skid in a vertical plane is substantially flat and of sufficient depth to secure strength and efficiency without bulk and without necessity of a departure from the desired streamline form.

It may be further stated that the mounting of the tail skid upon the rudder post 26 is only preferred when used in connection with the vertical rudder of the machine. The same type of skid may be equally as well used upon varied types of aeroplanes and the shock absorbing mechanism carried by any rigid aeroplane part.

While we have described our invention in detail in the present preferred embodiment it will be obvious to those skilled in the art that after understanding it that various changes and modifications may be made in the invention without departing from its spirit or scope. We aim, in the appended claims, to cover all such modifications and changes.

We claim:

1. In an aeroplane, the combination of a rudder movable laterally for steering purposes, a tail skid mounted beneath the rudder for vertical pivotal movement and for lateral pivotal movement independently of the rudder about its extended axis, mechanism for yieldingly resisting the vertical pivotal movement of the tail skid, and means enclosing said mechanism to minimize the resistance of the skid.

2. In an aeroplane, the combination of a rudder movable laterally for steering purposes, a rudder post, a vertically movable tail skid mounted beneath the rudder and carried by the rudder post, the tail skid being partly streamlined and movable later-

ally independently of the rudder, the rudder post defining the axis about which both the rudder and the tail skid move, mechanism for yieldingly resisting vertical pivotal movement of the tail skid, and means enclosing said mechanism to minimize the resistance of the tail skid considered as a while.

3. In an aeroplane, the combination of a rudder having a portion of its area cut away, a tail skid mounted beneath the rudder, and a substantially streamlined casing enclosing a portion of the tail skid, the casing, for the major part, being normally confined to the space defined by that portion of the rudder cut away.

4. In an aeroplane, the combination of a rudder, a tail skid, and a substantially streamlined casing enclosing a portion of the tail skid, the marginal lines of the casing and the marginal lines of the rudder being so relatively arranged that the lines of one merge uninterruptedly into the lines of the other.

5. A tail skid for aeroplanes including a substantially triangular skid mounted for swinging movement about a transverse axis, a vertically disposed skid support, means engaging the skid at a point rearwardly removed from its transverse axis to yieldingly resist its swinging movement, and pivot connections respectively between said means and the support and said means and the skid.

6. A tail skid for aeroplanes including a skid block movable laterally about a vertical axis, means engaging the skid block and movable with it to yieldingly resist its vertical movement, and a substantially streamlined casing enclosing said last mentioned means, said casing being movable laterally with the skid block about its vertical axis and fixed with regard to the skid block when the skid block is vertically displaced.

7. In an aeroplane, a rudder having a recess formed in it, a tail skid, shock absorbing mechanism for the tail skid, and a substantially streamline casing enclosing the shock absorbing mechanism and normally occupying the space formed by the recess in the rudder.

8. A tail skid for aeroplanes including a pivoted skid block, shock absorbing mechanism connected with the skid, means supporting both the skid and shock absorbing mechanism for lateral swinging movement and a substantially streamline casing enclosing the shock absorbing mechanism and a portion of the skid.

In testimony whereof we hereunto affix our signatures.

HENRY KLECKLER.
GLENN H. CURTISS.
